(57) **CLAIM**

The ornamental design for a single-dose cleansing unit, as shown and described.

DESCRIPTION

The patent or application file contains at least one drawing executed in color. Copies of this patent or patent application publication with color drawings(s) will be provided by the Office upon request and payment of the necessary fee.

FIG. 1 is a perspective view of a single-dose cleansing unit embodying our new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is a perspective view of the second embodiment of a single-dose cleansing unit embodying our new design;

FIG. 9 is a front view thereof;

FIG. 10 is a back view thereof;

FIG. 11 is a left view thereof;

FIG. 12 is a right view thereof;

FIG. 13 is a top view thereof;

FIG. 14 is a bottom view thereof;

FIG. 15 is a perspective view of the third embodiment of a single-dose cleansing unit embodying our new design;

FIG. 16 is a front view thereof;

FIG. 17 is a back view thereof;

FIG. 18 is a left view thereof;

FIG. 19 is a right view thereof;

FIG. 20 is a top view thereof;

FIG. 21 is a bottom view thereof;

FIG. 22 is a perspective view of the fourth embodiment of a single-dose cleansing unit embodying our new design;

FIG. 23 is a front view thereof;

FIG. 24 is a back view thereof;

FIG. 25 is a left view thereof;

FIG. 26 is a right view thereof;

FIG. 27 is a top view thereof;

(Continued)

FIG. 28 is a bottom view thereof;
 FIG. 29 is a perspective view of the fifth embodiment of a single-dose cleansing unit embodying our new design;
 FIG. 30 is a front view thereof;
 FIG. 31 is a back view thereof;
 FIG. 32 is a left view thereof;
 FIG. 33 is a right view thereof;
 FIG. 34 is a top view thereof;
 FIG. 35 is a bottom view thereof;
 FIG. 36 is a perspective view of the sixth embodiment of a single-dose cleansing unit embodying our new design;
 FIG. 37 is a front view thereof;
 FIG. 38 is a back view thereof;
 FIG. 39 is a left view thereof;
 FIG. 40 is a right view thereof;
 FIG. 41 is a top view thereof;
 FIG. 42 is a bottom view thereof;
 FIG. 43 is a perspective view of the seventh embodiment of a single-dose cleansing unit embodying our new design;
 FIG. 44 is a front view thereof;
 FIG. 45 is a back view thereof;
 FIG. 46 is a left view thereof;
 FIG. 47 is a right view thereof;
 FIG. 48 is a top view thereof;
 FIG. 49 is a bottom view thereof;
 FIG. 50 is a perspective view of the eighth embodiment of a single-dose cleansing unit embodying our new design;
 FIG. 51 is a front view thereof;
 FIG. 52 is a back view thereof;
 FIG. 53 is a left view thereof;
 FIG. 54 is a right view thereof;
 FIG. 55 is a top view thereof;
 FIG. 56 is a bottom view thereof;
 FIG. 57 is a perspective view of the ninth embodiment of a single-dose cleansing unit embodying our new design;
 FIG. 58 is a front view thereof;
 FIG. 59 is a back view thereof;
 FIG. 60 is a left view thereof;
 FIG. 61 is a right view thereof;
 FIG. 62 is a top view thereof;
 FIG. 63 is a bottom view thereof;
 FIG. 64 is a perspective view of the tenth embodiment of a single-dose cleansing unit embodying our new design;
 FIG. 65 is a front view thereof;
 FIG. 66 is a back view thereof;
 FIG. 67 is a left view thereof;

FIG. 68 is a right view thereof;
 FIG. 69 is a top view thereof; and,
 FIG. 70 is a bottom view thereof.
